INVENTOR
WINFRED T. POWELL.
BY *Frank M. Slough*

ATTORNEY

UNITED STATES PATENT OFFICE.

WINFRED T. POWELL, OF ROCHESTER, NEW YORK, ASSIGNOR TO THE STROMBERG-CARLSON TELEPHONE MANUFACTURING COMPANY, OF ROCHESTER, NEW YORK, A CORPORATION OF NEW YORK.

ELECTROMECHANICAL TELEPHONE SYSTEM.

Application filed January 11, 1919. Serial No. 270,632.

To all whom it may concern:

Be it known that I, WINFRED T. POWELL, a citizen of the United States, residing in Rochester, in the county of Monroe and 5 State of New York, have invented certain new and useful Improvements in Electro-mechanical Telephone Systems, of which the following is a full, clear, concise, and exact description.

- 10 My invention relates to a system of telephone circuits and apparatus designed for the interconnection for conversations of the telephones of a telephone exchange, and is directed more particularly towards the provision of a system wherein interconnection 15 between the telephone is effected through the agency of automatic apparatus under the control of a calling subscriber of the system.
- 20 My invention has for its principal object, the provision of means whereby interconnection between any two lines of a telephone exchange may be effected with the greatest possible ease and rapidity, by the use of circuits of the simplest form and least expensive character, and wherein the use of a 25 "normaline" or "stay-out" line switch organization is provided wherein the circuits are adequately controlled by the use of only 30 a single pair of relays in addition to the stepping magnet of the switch.

Another object of my invention is a provision of an improved test system; another object is the provision of an improved system 35 of interconnecting lines on terminating calls, that is, where connection is to be made with a called line.

Other objects of my invention and the invention itself will be made apparent from a 40 description of the apparatus and circuits, and the operation of the same which follows: in which description reference will be had to the accompanying drawing in which the figure shows my system diagrammatically at A. I show a substation on a line having conductors T and R which line we will describe as a calling line, and at B, is shown a substation on a line having line conductors V and W which line will be described 45 as a called line, although either line or other lines of the system not specifically illustrated are likewise equipped with circuits and apparatus and may be used either as

calling or called lines; at L, I show line switch mechanism of the "normaline" or 55 "stay-put" type having a stepping magnet ST, a line relay LR and a cut-off relay CO. At M is indicated a line switch mechanism having line apparatus, the stepping magnet being shown at TS, the line relay LE, and 60 the cut-off relay OC. At CN is shown one of a plurality of connector switch trunk circuits having controlling relays, circuit connections therefor and apparatus operating in connection therewith indicated, and to 65 which reference will be more fully had in the narrative of the operation which follows: connector or selective switch CN may be of any of the well known types and is specifically shown in the embodiment illustrated as of that type, wherein the connector switch wipers are elevated step by step under the control of the calling subscriber's dial, as CD for the substation A, to locate the group of terminals in which are located 70 the particular terminals to which connection must be made in order to connect with the called line; furthermore having a secondary stepping magnet which is subsequently caused to operate under the control of the 75 subscriber's substation dial to advance the switch wipers, as 41 and 42, and connect with the particular terminals associated with the called line.

Such a switch mechanism is well known 85 in the art and may be constructed in any one of a number of approved ways. For the purpose of this description, however, it will be assumed that the primary stepping is in a vertical upward direction and the secondary 90 stepping in a horizontal rotary direction. The set of terminals located by this movement of the connector switch is connected to a set of circuit conductors, comprising terminating call trunks which are for the purpose 95 of interlinking the connector switch wipers and the wipers of the called line individual switch, which called line individual switch, in this description the called line individual switch M, is then caused to perform a non-numerical switching operation 100 to advance its switch wipers 49, 50, 51, 52 and 53 under the control of the line switch controlling apparatus, to make connection with the set of contacts in their path, which 105 are connected to the terminating call trunk

conductors also connected as has been said, to the set of terminals in the connector switch bank to which connection has been made to the connector switch wipers.

5 If when connection is made with the terminating call trunk circuit terminals by the connector switch wipers the called line is busy and therefore not available for connection, the connector switch mechanism and 10 circuits will advance just the same as if the called line had been idle, except that in this latter case there will be no response by the called-for party and no operation of the connector switch circuits of apparatus under 15 the called subscriber's substation control. However, the called line individual switch will not be caused to move to cause its wipers to make connection with the terminals of the outgoing or terminating trunk circuit 20 leading from the connector switch bank, and connection will only be made to a source of busy tone current, common to a plurality of line circuits, so that there will be projected back through the circuits of the called 25 line switch and through the circuits of the connector switch, as CN, and through the circuits of the calling line switch L, back to the calling subscriber, the busy tone apprising the subscriber that the called-for line 30 is busy.

If the present invention is used in a system having only 100 lines, there will be 100 line switches, such as L and M, one of which is individual to each line. Each line switch 35 is provided with 20 sets of fixed contacts, 10 of which serve as terminals for trunks leading to directly operated switches, such as connectors, and other 10 contacts serve as terminals for incoming trunks which are 40 employed when a line is called. Since it has been assumed that 10 per cent trunking is employed, there will be 10 connector switches, each one of which has access to 100 terminals corresponding to the lines of the 45 system. In the present arrangement the so-called talking contacts and test contacts are not multiplied between the several connector switches, only the so-called starting conductor, such as 63, being multiplied between the 50 10 connector switches. Two of these multiplied connections from the starting conductor 63, are shown near the bottom of the drawing.

It will be understood that the number of 55 lines of the system as well as the number of the incoming and out-going trunks and connector switches may be varied according to the size and demands of the system, and that the mentioned numbers are merely used for 60 purposes of description.

In order to facilitate a better understanding 65 of my invention and the objects thereof, a description will now be had of the operation of the same made under the assumption that it is the subscriber at the substa-

tion A that desires to make a call, and that a connection is desired with the subscriber at the substation B located upon a line having the line switch M, and the line number of which line is assumed to be #20.

The subscriber at substation A, upon removing his receiver r, closes an energizing circuit for the line relay LR of the line switch L as follows: ground at G, contact 1 of the cut-off relay CO, line conductor T, 70 contact 2 of the substation hook switch, transmitter TR, receiver r calling device CD, line conductor R, contact 3 of the cut-off relay CO, winding of the line relay LR to the source of current.

The line relay LR operates and closes the following circuit: ground G, contact 1 of cut-off relay CO, contact 4 of line relay LR, winding of stepping magnet ST, contact 5 of said stepping magnet, resistance coil RE 80 to the source of current. Assuming the trunk upon which the wipers 6, 7, 8, 9 and 10 of line switch L are resting, to be busy, this above traced circuit will cause the stepping magnet ST to energize, break its own circuit at contact 5 and to then retract its armature. This causes the wipers 6, 7, 8, 9 and 10 to be stepped to the second row of terminals where nothing is found to cause the stepping magnet ST to remain deener- 90 gized, therefore it will continue to step the wipers forward until the fifth row of terminals is reached which are assumed to be the terminals of the first idle trunk tested by the line switch, L. Here the switch will 100 be stopped because ground GA will place a shunt around the stepping magnet winding 14, through the resistance of the winding 22 of the cut-off relay, CO which is low enough to prevent the stepping magnet ST from 105 again operating. This circuit is traced as follows: ground GA of connector CN, contact 16 of relay IMP, contact 18 of relay RL, normally closed shaft contact 19, test trunk 20, which is multiplied to a corresponding contact of all line switch banks of the group, terminal 15, wiper 6, contact 12 of relay LR, low resistance 22 of relay CO, contact 24 of relay CO, to one side of the stepping magnet winding 14. The other side of 110 the stepping magnet winding 14 has ground G on it as before traced. The stepping magnet winding 14 does not get sufficient current 115 to energize its armature, therefore the wipers 6, 7, 8, 9 and 10 of line switch L remain on the trunk leading to connector CN.

This same ground, GA, which was traced to the coil winding 14 also goes through contact 5 of stepping magnet ST, resistance coil RE to the source of current. This circuit, 125 which includes winding 22 of relay CO, causes the cut-off relay CO to operate and disconnect the line switch battery bridge from the calling line at contacts 1 and 3.

The line conductor T is extended by way 130

of contact 27 of relay CO, wiper 10, terminal 28, trunk wire 29 and winding of impedance coil B to ground GB at connector CN. Line conductor R is extended by way 5 of contact 30 of relay CO, wiper 9, terminal 31, trunk wire 32 and winding of impulse relay IMP to the source of current. The closed circuit of the substation A in addition to the above traced circuit causes the energization 10 of relay IMP, which in turn operates relay RL over the following circuit: ground GA, contact 17 of relay IMP and winding of relay RL to battery. The instant that relay IMP operates, this particular connector CN is made busy to other calling line switches like L because ground is taken off the test trunk 20 by the opening of contact 16. Ground will not again be placed on trunk 20 until disconnection is made. It 15 is kept off of trunk 20 during the impulsing of relay IMP because of the fact that relay RL, which is slow releasing, holds its armature attracted, and maintains contact 18 opened while relay IMP vibrates its contacts. Upon disconnection this ground GA is not placed on trunk 20, to cause this trunk to test idle, until the shaft of connector CN reaches normal and closes off normal contact 19.

30 When the relay CO of line switch L operates, as previously described, it opens its own low winding 22 at contact 24 and closes its own high resistance winding 23 which locks itself over the following circuit:—

35 ground GC, contact 33 of connector release magnet REL, holding trunk 34, terminal 35 and wiper 8 of line switch L, high winding 23 of relay CO, contact 21 of relay CO, contact 5 of stepping magnet ST, resistance RE 40 to the source of current. The operation of relay CO also disconnects the stepping magnet circuit ST from the trunk 36 of connector CN at contact 26 and places the common busy tone wire 37 on the trunk 36, through contact 25 and condenser 38, for a purpose to be later described. The operation of the relay CO also allows line relay LR to retract its armatures by opening its circuit at contact 3.

45 Assume the number desired by the calling subscriber at substation A to be 20 and that number 20 is the substation shown at B. The calling subscriber now operates his calling device for the first digit 2 of the called number, whereby the substation impulse springs (not shown but well understood) are operated twice momentarily, each time breaking the circuit of the connector impulse relay IMP. The relay RL of the connector being slow releasing does not deenergize during the momentary interruptions of its circuit by the impulse relay IMP, and consequently each time the latter deenergizes, an impulse is transmitted through the 50 primary magnet PM. This circuit extends

from ground GA, contact 16 of relay IMP, contact 39 of relay RL, winding of "change-over" relay CH, side switch 40 and first position thereof, winding of primary magnet PM to the source of current. The primary magnet PM receives two impulses over this circuit and operates to raise the connector switch wipers 41, 42, 43 and 44 to a position opposite the second level of bank contacts. The relay CH, which is included in series 70 with the primary stepping magnet PM and is slow releasing, remains energized during the entire time that impulses are being transmitted through it and operates to close the circuit of the escape magnet ESC. The 75 circuit for operating the magnet ESC extends from ground GD, contact 45 of relay CH, winding of magnet ESC, resistance coil 46 to the source of current. After the last impulse is delivered, the relay CH releases 80 and opens the circuit for magnet ESC, which, upon deenergizing, permits the side switch wipers 40, 47 and 48 to advance from first to second position. The movement of the side switch wiper 40 from first to second 85 position transfers the impulse circuit from the primary magnet PM to the secondary magnet SM.

The calling subscriber now operates his calling device for the last digit 0, in response to which the connector impulse relay IMP operates to transmit ten impulses through the secondary magnet SM in series with the relay CH, whereby the shaft wipers 41, 42, 43 and 44 are rotated onto the contacts of the desired line. The said circuit extends from ground GA, contact 16 of relay IMP, contact 39 of relay RL, winding of relay CH, side switch wiper 40 and second position thereof, winding of secondary magnet SM to the source of current. The relay CH operates in response to the impulses for this digit in the same manner as for the previous digit to cause the escape magnet ESC to advance the side switch 100 wipers 40, 47 and 48 one more position, i. e., from second to third position.

By the engagement of the side switch wiper 48 with its third position contact point, a connection is completed for energizing the escape magnet as follows:—ground GD, side switch wiper 48, and third position contact thereof, winding of magnet ESC, resistance coil 46 to the source of current. This energizes the escape magnet 115 120 but does not allow the side switch wipers to move away from the third position as they are advanced upon the release of the escape magnet. Side switch wiper 47 completes a circuit to cause the called line switch M to step around to a point on its bank corresponding to the connector CN which connected with it, i. e., the line switch M at this time will advance to the sixth 125 row of contacts on its bank (of those shown) 130

at which point called line switch wipers 49, 50, 51, 52 and 53 will rest on terminals 54, 55, 56, 57 and 58 respectively. As the connector wipers 41, 42, 43 and 44 are now 5 resting on contacts 59, 60, 61 and 62 respectively, it will be seen that connection may now be established between calling substation A and called substation B. The circuit for causing line switch M to advance 10 to the point associated with connector CN, as above described, is as follows: ground GE, low resistance impedance coil X, side switch 47 and third position thereof, connector wiper 44, terminal 62, trunk wire 63, contact 64 of relay OC of called line switch M, winding 65 of stepping magnet TS, contact 66 of magnet TS, resistance coil RS to the source of current. This circuit causes 15 the magnet TS to advance in the same manner as described for the calling line switch L, until the wipers reach the sixth row of terminals when they will be stopped by the following circuit:—ground GE, low resistance impedance coil X, contact 67 of 20 relay TT, contact 68 of relay CI, connector wiper 41, terminal 59, trunk wire 69, terminal 57 and wiper 52 of called line switch M, contact 70 of relay LE, low resistance winding 71 and contact 72 of relay OC to 25 one side of stepping magnet TS. The other side of TS also goes to ground GE as previously traced, therefore, as the stepping magnet TS is shunted by the low resistance winding 71 of relay OC, it will not again 30 operate. This above traced circuit which went through winding 71 of relay OC, in addition to causing line switch M to stop on the sixth row of terminals, causes relay OC to operate. Relay OC locks over the 35 following circuit:—ground GE, winding of impedance coil X, side switch wiper 47 and third position thereof, winding of relay TT, connector wiper 43, terminal 61, trunk wire 73, terminal 56 and wiper 51 of 40 line switch M, high resistance winding 74 of relay OC, contact 75 of relay OC, contact 66 of magnet ST, resistance coil RS to the source of current. This circuit causes relay TT to operate whose function will be 45 later described.

Relay OC, in operating, removes the line switch M battery bridge from the called line by opening contacts 76 and 77. Relay OC also extends the called line 50 conductors V and W to the line wipers 41 and 42 of the connector CN by way of wipers 49 and 50 of called line switch M. Relay OC also extends the common battery 55 busy tone wire 37 by way of condenser 78, contact 79 of relay OC, trunk wire 63, connector terminal 62, connector wiper 44 to side switch 47. The tone will not be heard 60 by the calling party at this time because it is held disconnected from the calling line 65 by contact 67 of relay TT.

The called substation B is now signalled by means of the following circuit:—common generator GN, common interrupter IN, common lamp LP, winding of trip relay TP, contact 80 of relay CI, connector wiper 42, 70 terminal 60, trunk wire 81, terminal 55 of called line switch M, line switch wiper 50, contact 82 of relay OC, called line conductor W, condenser k, ringer ri, hook switch contact 84, conductor V, contact 83 of relay OC, 75 line switch wiper 49, terminal 54, trunk wire 69, terminal 59, connector wiper 41, contact 68 of relay CI, contact 85 of relay TT, resistance coil 86, ground, ground GH, through the battery, common resistance coil 87 to the 80 other side of the generator GN. Because of the low resistance coil 86 included in the return path for this signaling current, part of it will be forced through condenser 92, trunk wire 29, terminal 28, line switch wiper 10, 85 contact 27 of relay CO; line conductor T, substation apparatus A, line conductor R, contact 30 of relay CO, line switch wiper 9, terminal 31, trunk wire 32, winding of relay IMP, through the source of current to 90 ground GL. This causes an audible signal to be given the calling subscriber, notifying him that the called party's line is being rung. Upon the response of the called subscriber at substation B, relay TP, which is included 95 in the above traced signaling circuit, operates because of the closed path for direct current which is formed by closing contact 88 at the hook switch. Relay TP, upon energizing, releases the escape magnet ESC, allowing side switch wipers 40, 47 and 48 to advance to the fourth position. This circuit is traced as follows:—ground GG, contact 89 of relay TP to the side of the escape magnet ESC which goes to the source of current 100 through resistance coil 46. This short circuits magnet ESC and causes it to release.

Relay CI now energizes over the following circuit:—ground GD, side switch wiper 48 and fourth position thereof, winding of relay 110 CI to the source of current. In passing it may be said that this above circuit is also closed when side switch wiper 48 is in the second position thereby energizing relay CI. This is for the purpose of preventing ground, 115 through low resistance impedance coil X, being extended by way of contact 67 of relay TT, contact 68 of relay CI (which would otherwise be deenergized), connector wiper 41, a terminal like 59 being contacted with as 120 wiper 41 advances over it, trunk wire 69, line switch terminal 57, wiper 52 of some line switch like M resting unused at this point, contact 70 of relay LE, low resistance winding 71 of relay OC, contact 72 of relay OC, 125 contact 66 of magnet TS, resistance coil RS to the source of current. If this could happen a relay OC of line switch M would be energized unnecessarily as a connector passes over a contact upon which the line switch 130

was standing. By operating relay CI, which disconnects the low resistance path to ground this condition is avoided. The ground GF through winding 90 of coil AB is connected 5 in this circuit but because of the high resistance winding 90 of coil AB being in series with the very low resistance winding 71 of relay OC, the latter will not operate.

The called subscriber now gets talking current as follows: ground GF, winding 90 of 10 talking bridge coil AB, connector wiper 41, terminal 59, trunk wire 69, line switch terminal 54, line switch wiper 49, contact 83 of relay OC, conductor V, substation B, conductor W, contact 82 of relay OC, line switch wiper 15 50, terminal 55, trunk wire 81, terminal 60, connector wiper 42, contact 92 of relay CI, winding 91 of coil AB to the source of current. The calling subscriber gets talking 20 current through relay IMP and battery feed coil B the circuit of which was previously traced. The voice currents pass between the two through condensers 92 and 93.

If the called line switch M is busy when 25 the connector CN lands on the terminals associated with it, the connector side switch will advance to the third position in the same manner as when calling an idle line switch. If the called line switch is busy either because 30 of an originating or terminating call, its cut-off relay OC will be in its energized position, therefore when connector side switch wiper 47 reaches the third position, the ground GE, which on a connection to an 35 idle line caused the line switch to step, will now find an open point at contact 64 of relay OC, and stepping magnet TS of the called line switch M will not be disturbed. The calling subscriber will get the busy tone as 40 follows:—ground GK, winding 94 of busy induction coil IND, busy tone interrupter BT, through the source of current to ground at GJ. This circuit induces a tone into the winding 95 of busy induction coil IND which is caused to flow over the following 45 circuit:—ground GK, winding 95 of busy induction coil IND, busy wire 37, condenser 78, contact 79 of relay OC, trunk wire 63, terminal 62, connector wiper 44, side switch wiper 50 47 and third position thereof, impedance coil X to ground GE. Because of the high impedance of coil X, part of this tone current will be forced by way of contact 67 of relay TT (this relay can not energize on a connection to a busy line switch because line switch wiper 51 will not step to the point on its bank corresponding to this connector), contact 68 of relay CI, condenser 92, trunk wire 29, terminal 28, calling line switch wiper 10, 55 contact 27 of relay CO, line conductor T, substation apparatus A, line conductor R, contact 30, of relay CO, line switch wiper 9, terminal 31, trunk wire 32, relay IMP of connector CN, through the source of current to 60 ground GL. As this circuit includes the

telephone at A, the calling subscriber will hear the busy tone.

If the called line becomes idle while a connector CN is waiting on its terminals, the called line switch will immediately advance to the proper point when connection will be made as previously described for a case where the called line was not busy.

If more than one connector is waiting on the terminals of a line when it becomes 75 idle, the called line switch can only connect with one of them (which will be the one corresponding to the next nearest point on the line switch bank) because the called line switch must step to a different point on 80 its bank for each connector which calls it and the line switch wipers can only rest on one set of terminals at a time.

After the conversation is completed, the connection is released, by the hanging up 85 of the calling subscriber's receiver, in the following manner:—The circuit for relay IMP is opened by contact 2 at the hook switch of substation A which allows relay IMP to deenergize and open the circuit for 90 relay RL at contact 17. Relay RL, after a short time, releases and closes a circuit from ground GA, contact 16 of relay IMP, contact 18 of relay RL, off normal contact 96, winding of release magnet REL to the 95 source of current. The magnet REL upon energizing, restores the connector switch shaft and side switch to normal after which its own circuit is broken at off normal contact 96. The magnet REL, upon energizing 100 also opens the circuit leading to the winding 23 of the calling line switch cut off relay CO. This circuit is opened at contact 33 of magnet REL and allows the line switch cut off relay CO to deenergize. 105

The connector is now in position to be again selected because there is a ground GA, through contact 16 of relay IMP, contact 18 of relay RL, off normal contact 19 on its test trunk 20.

Both the calling and the called line switches L and M remain where they were during conversation, until again used.

It will of course be understood that the lines having the substations A and B, may 115 as in this description, be of the same group of lines having access to the same group of connector switches. It will be understood, however, that by simply providing the usual first selector, and if desired, second selector switch mechanisms between the line switches of a group and connector switches, such as CN, for a plurality of groups, that the system may be made of any size and use may be had of the principles of trunking which are in vogue in this art at the present time by virtue of which the advantages of such trunking circuits may be had, and in addition the advantages of my system may be added thereto. 120 125 130

In the embodiment illustrated, although the first selector switch is not described in detail, it is indicated by its switch wipers connected to the conductors 29, 32, 34 and 5 20, and which are shown in the drawing as engaging passive contacts of the connector switch, CN. It will be understood in the art how such engagement will be controlled by the calling switch mechanism, and no 10 detailed description of such operation as may be necessary to cause such engagement, will therefore herein be had.

It will be understood, that if desired, the lines having the substations A and B may 15 have common access by their respective line switches L and M to the same trunk circuit, such as the trunk circuit CN, for instance, in such a case the line switch sets of contacts consisting of the contacts 28, 20 31, 35, 105 and 15 of the line switch L and which set of contacts are associated with the connector switch CN, may be multiply connected to the line switch set or contacts 28^a, 31^a, 35^a, 105^a and 15^a of the line switch M. 25 Although I have illustrated and described a specific embodiment of my invention for the purpose of imparting a clear understanding of the same, it will be understood that I am aware that numerous and extensive departures may be made from the embodiment illustrated without departing from the spirit of the invention, but what I 30 claim as my invention is defined in the following claims:

35 1. In a telephone system, the combination with a plurality of telephone lines, a plurality of connector switches, calling line apparatus for directively controlling said connector switches means including a non-numerical switch to interconnect a calling one of the said lines with an idle one of the said switches, a test wiper for the said connector switch, passive contacts, one for each of the lines adapted to be engaged by the 40 said test wiper, controlling apparatus for the said connector switches, a circuit for each of the lines leading to said contact for that line on each connector switch, and means responsive to the continuity of the 45 said circuit when the said test wiper engages a called line contact to extend a talking circuit from the calling line to the called line through the said connector switch.

50 2. In a telephone system, the combination with a plurality of telephone lines, controlling apparatus for each line, a plurality of selective switches having wipers, a line switch for each of the lines, separate sets of calling and called contacts for each of the 55 said line switches, means responsive to the closure of calling line circuit conductors to operate a calling line switch to connect with an idle one of the said selective switches through the calling contact set of the calling line switch, means under the control of

calling line apparatus and connected selective switch to operate the called line switch to cause it to make connection with a called set of contacts of the called line switch, and means including wipers of said selective 70 switch for interconnecting the said calling line switch calling contacts and said called line switch called contacts to extend a talking connection between the calling and called lines through all of the said switch contacts.

3. In a telephone trunking system, the combination with a plurality of telephone lines, line switches for the lines, active switch wipers for the line switches connected to circuit conductors individual to the lines, successive sets of passive contacts for each of the line switches, some of the said sets being connected to circuit conductors leading to one type of trunk circuit, other sets being connected to circuit conductors leading to another type of trunk circuit, means responsive to a closure of the line conductors of a calling line to move the active switch wipers of said calling line switch into engagement with a set of contacts, whose connected circuit conductors lead to a trunk circuit of the first type, switching means responsive to the directive control of the calling substation apparatus to complete a connection between selected trunk circuit apparatus and a trunk circuit of the second type which leads to called line switch apparatus to cause the said called line switch to advance its active switch wipers to make connection with the set of contacts connected to the trunk circuit of the second type with which the trunk circuit apparatus of the said trunk circuit has made connection.

4. In a telephone system, the combination with a plurality of telephone lines, substations for the said lines, a line relay for each of the lines in circuit with the line substation, a line switch for each of the lines, active switch contacts and passive switch contacts for the said line switch, propelling means for propelling the active switch contacts of a line switch to cause them to make contact successively with different sets of passive switch contacts, the said passive contact sets being in two groups, one group being incoming contact sets, the other group being outgoing contact sets, a stopping circuit for the said propelling means having two branches, one of the said branches being normally closed and the other of said branches being normally open, means responsive to the continued closure of the closed branch to cause the said active switch contacts to be stopped when they engage the contacts of a particular trunk circuit associated with a given contact of one of the groups, and means responsive to the closure of the other branch and the opening of the first branch to cause the said active contacts to stop when in en- 130

gagement with the first engaged set of contacts of the other group.

5. In a telephone system, the combination with a plurality of telephone lines, substations for the said lines, a line relay for each of the lines in circuit with the line substation, a line switch for each of the lines, active switch contacts and passive switch contacts for the said line switch, propelling 10 means for propelling the active switch contacts of a line switch to cause them to make contact successively with different sets of passive switch contacts, the said passive contact sets being in two groups, one group being incoming contact sets, the other group being outgoing contact sets, a stopping circuit for the said propelling means having two branches, one of the said branches being normally closed and the other of said 15 branches being normally open, means responsive to the continued closure of the closed branch to cause the said active switch contacts to be stopped when they engage the contacts of a particular trunk circuit associated 20 with a given contact of one of the groups, and means responsive to the closure of the other branch and the opening of the first branch to cause the said active contacts to stop when in engagement with the first 25 engaged set of contacts of the other group, said line relay magnet for an associated line switch controlling the opening of one of the said branch circuits, and the closure of the other branch circuit.

35 6. In a telephone system, the combination with a plurality of telephones, a line relay for each of the lines, a cut-off relay for each line relay, a common source of busy tone current, a link circuit adapted to be connected 40 with a calling line, a contact of the said link circuit adapted to make connection with a contact of a desired called line, and a busy tone circuit arranged to extend a connection between the said common source of busy tone 45 current and the talking conductors of a calling line, including normally open contacts of the calling line cut-off relay, said link circuit contact, and said calling line link circuit connecting means.

50 7. In a telephone system, the combination with a plurality of telephone lines, substations for the said lines, line switches for the said lines, said line switches comprising a set of active switch wipers and sets of passive 55 switch contacts adapted to be successively engaged by the movement of the said active switch wipers, means to move the said active switch wipers, the said passive sets of contacts comprising calling and called sets, 60 means responsive to the connection of a substation to a calling line circuit to cause the said switch wiper moving means to operate, a plurality of link circuits, incoming terminals and outgoing terminals for the said

link circuits, the incoming terminals and the outgoing terminals of the different link circuits being connected to different contact sets of the different line switches, means responsive to the electrical condition of an incoming contact of the set of contacts of a given 70 link circuit to stop the movement of a calling line switch when its active switch contacts come into engagement with the said contact set, selective switching means for the said link circuit under the control of calling substation apparatus to cause the movement of the called line switch active contacts, and controlling means associated with the said selective switching means to alter the electrical condition of a contact of a set of contacts associated with the called line switch and with the said link circuit, which set of contacts is with reference to the said link circuit an outgoing set of contacts for the said called line switch, whereby the movement of the said called line switch is stopped when its active switch contacts engage the said outgoing contact set.

8. In a telephone system, the combination with a plurality of telephone lines, substations for the said lines, line switches for the said lines, said line switches comprising a set of active switch wipers and sets of passive switch contacts adapted to be successively engaged by the movement of the said active 90 switch wipers, means to move the said active switch wipers, the said passive sets of contacts comprising calling and called sets, means responsive to the connection of a substation to a calling line circuit, to cause the 95 said switch wiper moving means to operate, a plurality of link circuits, incoming terminals and outgoing terminals for the said link circuits, the incoming terminals and the outgoing terminals of the different link circuits being connected to different contact sets of the different line switches, means responsive to the electrical condition of an incoming contact of the set of contacts of a given link circuit to stop the movement of a calling line switch when its active switch contacts come into engagement with the said contact set, selective switching means for the said link circuit under the control of calling 100 substation apparatus to cause the movement of the called line switch active contacts, controlling means associated with the said selective switching means to alter the electrical condition of a contact of a set of contacts associated with the called line switch and with the said link circuit, which set of contacts is with reference to the said link circuit an outgoing set of contacts for the said called line switch, whereby the movement of the said called line switch is stopped when its active switch contacts engage the said outgoing contact set and a calling circuit extended from the calling line, through 105 110 115 120 125

the said link circuit, through active contacts of the calling and called line switches and passive incoming and outgoing contacts of the calling and called line switches respectively, for the said link circuit.

9. In a telephone system, the combination with a plurality of subscribers' telephone lines, line switches for the lines, numerical switches adapted to be selected by a calling line switch, and means under the control of a numerical switch to cause the operation of a called line switch and a talking circuit established through contacts of the line switches of calling and called lines and of said numerical switch.

10. In an automatic telephone system, a plurality of telephone lines, a single individual line switch for each line, a numerical switch arranged for primary and secondary movements, outgoing lines from said numerical switch, means for causing the individual line switch of the calling line to seize said numerical switch, means to operate said numerical switch to seize an outgoing line, and means to cause the line switch of the called telephone line to hunt for the seized outgoing line, said calling and called

line switches and said numerical switch being retained in the established connection.

11. In a telephone system, the combination with a plurality of subscribers' telephone lines, line switches normally remaining in the position last used, and a numerical switch adapted to be selected by a calling line switch, of means under the control of a numerical switch to cause the operation of a called line switch, and a talking circuit extending through the line switches of calling and called lines and said numerical switch.

12. In a telephone system, the combination with a plurality of subscribers' telephone lines, line switches for the lines, individual operating means for each of said line switches, and numerical switches adapted to be selected by a calling line switch, of means under the control of a numerical switch to cause the operation of the line switch of the called line, and a talking circuit established through contacts of the line switches of calling and called lines and of said numerical switch.

In witness whereof, I hereunto subscribe my name this 9th day of Jan., A. D. 1919.

WINFRED T. POWELL.
